UNITED STATES PATENT OFFICE.

PHILIP N. BRAUN, OF SYRACUSE, NEW YORK, ASSIGNOR TO THE PROSPERITY CO. INC., OF SYRACUSE, NEW YORK, A CORPORATION OF NEW YORK.

GARMENT-PRESSING MACHINE.

Application filed December 30, 1921. Serial No. 525,884.

To all whom it may concern:

Be it known that I, PHILIP N. BRAUN, a citizen of the United States, and a resident of Syracuse, in the county of Onondaga and 5 State of New York, have invented certain new and useful Garment-Pressing Machines, of which the following is a specification.

This invention relates to steam pressing machines as garment presses and the like, 10 and has for its object a particularly simple and efficient arrangement of the operating members or pedal levers by which the passage of steam through the garment being pressed can be operated at will independently or by the same foot operating the main 15 actuating pedal for actuating the press head without shifting the foot from one pedal to another.

The invention consists in the novel features and in the combinations and constructions hereinafter set forth and claimed.

In describing this invention, reference is had to the accompanying drawings in which like characters designate corresponding parts 25 in all the views.

Figure 1 is a fragmentary prospective view of a garment pressing machine embodying my invention.

Figure 2 is an enlarged fragmentary plan view of the main pedal and the pedal for controlling the passage of steam to the garment being pressed.

The machine may be of any suitable size, form and construction and is of the type, 35 set forth in Patent No. 1,252,988, issued Jan. 8, 1918, to A. C. Austin.

Such machine comprises generally, a frame 1, a press head or lower buck 2 and an upper pressing head 3 movable toward and 40 from the buck 2 and suitably supported to be moved, mechanism for moving the upper press head toward the buck comprising a pedal lever 4 pivoted at 5 to the frame and connected by suitable mechanism such as 45 shown in said patent to the upper press head 3, and a valve-controlled conduit for controlling the flow of steam through one or the other of the pressing elements 2, 3 here shown as the lower buck 2 and through the 50 cloth, operating the valve of such conduit and having its foot engaging portion extending crosswise of the foot engaging portion of the pedal 4 and projecting above the face of the pedal 4 in order to be operated

by the same foot engaged with the foot engaging portion of the pedal 4.

6 designates the valve casing connected in the conduit for the steam or other fluid.

7 is a reciprocally movable rod for operating the valve in the casing 6.

8 is the pedal for operating the rod 7, the pedal being pivoted at 9 to the main frame and having a foot engaging portion 10 having a portion 10a extending under the foot engaging portion or plate 11 of the main pedal 4 and being spaced apart far enough from the portion 11 to permit the lever 4 to be operated without operating the pedal 8, but having a projection 12 extending above the plane of the plate 11 of the 70 pedal 4 when the pedal 4 is depressed;

and here shown as projecting through a hole 14 in said plate 11, in order to be engaged if desired, with the same foot used to operate the pedal 4 without shifting such 75

foot. The pedal 4 and the toggle mechanism operated thereby locks itself in depressed position as will be understood by those skilled in the art and an additional 80

pedal 14 is employed to operate parts which give the initial opening impulse to the lever 4, these features all being old in the art, and shown in the patent hereinbefore referred to.

In operation, the operator depresses the 85 pedal 4 by pressing his foot on the plate 11 thereof thereby bringing the head 3 down toward the face of the lower buck 2 and pressing the garment or other article on the lower buck 2.

If it is desired, to pass steam through 90 such article the operator depresses the projection 12 with the toe of the same foot thus actuating the lever 8 and opening the valve of the casing 6 if it is desired to pass 95 steam through the garment when the pressing head is up the operator presses the lever 8 in the ordinary manner by engaging the foot with the plate 10. Or the operator may

so place his foot on the plate 11 of the pedal 4 that his foot covers the hole 14 so that when the pedal 4 is depressed the lever 8 is also operated by the same operation.

What I claim is:

A pressing machine including pressing elements, one of which is movable toward and from the other, a valve controlled conduit for supplying steam to the face of one

of said elements, a pedal for actuating the movable element, said pedal having a foot plate rigid therewith, a second pedal for controlling the valve of said conduit, the foot plate being formed with an opening in its foot engaging portion and the second pedal having a projection extending through

said opening, substantially as and for the purpose set forth.

In testimony whereof, I have hereunto ¹⁰ signed my name, at Syracuse, in the county of Onondaga, and State of New York, this 9th day of December, 1921.

PHILIP N. BRAUN.
